CARBURETOR

Robert F. Bracke, Chicago, Ill.

Application February 25, 1935, Serial No. 7,843

5 Claims. (Cl. 261—64)

My invention pertains to carburetors and is particularly concerned with a fuel-lift carburetor having two or more fuel injecting systems.

An object of my invention is to provide a carburetor having an improved air valve.

Another object is to provide a carburetor having a plurality of air valves and improved means for preventing fluttering of these air valves.

Another object is to provide a carburetor wherein the operation of the air valve is stabilized.

Another object is to provide a carburetor wherein the fluid passing therethrough is prevented from eddying.

Another object is to provide a carburetor wherein the fuel feed nozzle delivers at a point approximately in the region of highest suction, and wherein this point of delivery is so located relative to the other parts of the carburetor as to prevent freezing of any of the operative parts.

Another object is to provide an improved carburetor which is simple and rugged in construction, efficient and reliable in operation, and economical to manufacture.

Other objects and advantages will become apparent as the description proceeds.

In the drawings,

Figure 1 is a top plan view of a carburetor embodying my invention;

Figure 2 is a vertical section taken on the line 2—2 of Figure 1;

Figure 3 is a vertical section taken on the line 3—3 of Figure 1, and

Figure 4 is a diagrammatic view of a carburetor embodying my invention.

Referring to the drawings, I have shown my carburetor as comprising an upper casting A and a lower casting B secured together by bolts 10 and having an airtight gasket 12 firmly clamped between the two castings. The lower casting B is indicated as attached to a part C of an inlet manifold for an internal combustion engine, there being a suitable, airtight gasket 14 interposed between the manifold and the carburetor.

The carburetor shown is indicated as having two nozzles 16 and 18 supplied from a common fuel chamber 20. Each nozzle is in the form of a Venturi tube and has an air inlet exposed to atmosphere and leading to a restricted throat 22 terminating at a step just below which are the diagonal fuel feed passages 24 which connect the interior of the nozzle with an annular chamber 26. The annular chamber 26 surrounding each nozzle is connected by a duct 28 to a centrally-

located bore 30 (Figure 3) into the lower end of which is threaded a member 32 providing a knife-edged orifice through which communication is established with the interior of a cylinder 34, having its lower end located slightly above the bottom of the fuel chamber 20.

A piston 36 is located in the cylinder 34 and has a series of ports 38 through which fuel is drawn from the fuel chamber 20 to the nozzles 16 and 18. When the engine is idling the upper ends of ports 38 are substantially closed by a valve disk 40 having a small orifice 42 which permits of the passage of sufficient fuel for idling of the engine. When the engine is operating at part of full throttle, the valve disk 40 is sucked upwardly away from the upper ends of ports 38 to permit the flow of additional fuel to the nozzles 16 and 18.

The piston 36 and cylinder 34 constitute parts of an accelerator pump which is operated in one direction by a piston rod 44 and in the opposite direction by spring 46. The piston rod 44 rests on one end of lever 48 pivoted at 50 and having an intermediate portion resting on the cam 52 attached to one end of the throttle valve shaft 54. The throttle valve shaft 54 is provided with an arm 56 adapted for connection to the usual throttle valve controls.

The throttle valves are shown in the almost closed position which they assume when the engine is idling and in this position of the throttle valves and their shaft, the accelerator pump piston 36 is in its lowest position. A metering pin 58 has its enlarged upper end located in the knife-edged orifice provided by member 32 when the throttle valve is in the idling position. As the throttle valves are opened, the piston 36 is raised and the tapered upper end of metering pin 58 goes upwardly in the knife-edged orifice, permitting a progressively increased space affording 40' freer flow of fuel to the nozzles 16 and 18. When the engine is operating at full throttle the enlarged upper end of metering pin 58 is located entirely above the knife-edged orifice to permit maximum flow of fuel to the nozzles.

When the throttle is opened quickly through an appreciable range of movement, the piston 36 pumps an additional supply of fuel to the nozzles. If the throttle were opened quickly over a large range of its movement, too much fuel would 50 be thus pumped to the nozzles, and to prevent this I have provided the piston 36 with relief ports 60 which are normally closed by an annular valve 62 held against the lower ends of these ports by spring 64. When the piston 36 55-

makes a quick and long upward movement, valve 62 moves away from the lower ends of the ports 68 to permit back flow of fuel past the piston 36.

The nozzle 16 discharges into a mixing chamber 66 and the nozzle 18 discharges into a separate mixing chamber 68. Both mixing chambers receive their supplies of secondary air from a common air horn 70 centrally-located above the mixing chambers 66 and 68. Intermediate the air horn 70 and the mixing chamber 66 is an air valve 72 consisting of a disk of metal eccentrically mounted on a shaft 74. A second air valve 76 is located between the air horn 70 and the other mixing chamber 68. The valve 76 is identical with the valve 72 and is similarly mounted on the common shaft 74.

The common shaft 74 for the two air valves 72 and 76 carries an arm 78 at one end, this arm being connected through link 80 to the piston 82 of an air dashpot cylinder 84. A spring 86 is located in the cylinder 84 and urges the piston 82 upward, thereby tending to close the air valves 72 and 76, as indicated in Figure 2.

The particular structure and arrangement of these air valves and their associated mechanism constitute an important feature of my invention. The disk air valves 72 and 76 can be manufactured accurately and economically. The eccentric mounting of these valves provides larger areas on one side of the mounting shaft than on the other and, since the lower sides of these valves are exposed to the suction in the mixing chambers, the action of the suction on the larger areas overcomes the action of the suction on the smaller areas and opens these valves against the resistance of the spring 86.

It should be noted that the suction acting on these valves pulls downwardly on the common shaft 74, whereas the reaction of the spring 86 tends to lift this shaft. This results in a partial balancing of these forces so that the shaft 74 is a floating shaft to the extent that these forces balance. Because of this balancing, the shaft 74 rests lightly in its bearings and turns easily under all conditions and without any tendency to bind.

The mounting of the two air valves 72 and 76 on a common shaft also has another important advantage. Because of manufacturing variations inherent in the structure of every air valve, each air valve has a tendency to flutter at a slightly different period of vibration. By mounting the two air valves on a common shaft, the different periods of vibration of the two valves dampen or offset each other and steadier operation, free from fluttering, results.

Most of the secondary air admitted past each air valve flows between the right-hand side of the air valve and the opposing wall of the passage in which the air valve is located. The periphery of this right-hand part of the air valve and the cooperating opposing wall constitute a restriction through which the air must pass and produce an effect generally similar to that produced by a Venturi tube. Because of this action, the point in each mixing chamber where the greatest suction occurs is a short distance below the right-hand side of the associated air valve, and in order to take advantage of this fact, I so arrange the nozzles 16 and 18 that the discharge end of each nozzle is located immediately below its cooperating air valve and at the point of approximately greatest suction when the throttle is wide open and very close to the point of greatest suction when the throttle is partly open.

Immediately below the air valve shaft 74 I provide a metal strip 88 which extends across both mixing chambers and functions as a baffle to prevent the formation of eddy currents in the mixing chambers. If this baffle 88 were not provided, the secondary air rushing by the right-hand side of each air valve would have a tendency to swirl backwardly and upwardly after passing the air valve to satisfy the point of maximum suction formed by this air valve. The location of the baffle 88 effectively prevents this swirling or eddying action of the air passing the right-hand side of each air valve. This baffle 88 also directs the air passing the left-hand side of each air valve and further constitutes a means for stabilizing the opening movements of the air valves.

The lower end of each mixing chamber communicates with a separate throttle bore and each throttle bore in turn communicates with a separate part of the manifold C. A separate throttle valve is located in each throttle bore, the two throttle valves being attached to a common shaft 94.

The nozzle 16 has a set of radial ducts 90 spaced a short distance below the diagonal passages 24. These radial ducts 90 communicate with a space 92 located at the upper end of conduit 94 which opens into the throttle bore for the nozzle 16 at a point below the throttle valve located therein. The conduit 94 has a needle valve 96 whereby the idling operation of the nozzle 16 may be accurately adjusted.

The nozzle 18 is provided with a series of radial ports similar to the ports 90 of nozzle 16, and the radial ports of nozzle 18 are in communication with a conduit similar to conduit 94 but opening into the throttle bore associated with the nozzle 18 and at a point below the throttle valve therein. This conduit is controlled by a needle valve 98 similar to the needle valve 96. By means of needle valves 96 and 98, the idling operation of the nozzles 16 and 18 may be independently adjusted.

The fuel enters the fuel chamber 20 through a pipe 100 leading from the main fuel tank which is located below the chamber 20. Float 102 is located in the fuel chamber 20 and controls the usual inlet valve 104. The fuel is drawn into the fuel chamber 20 from the main fuel tank by the suction maintained in the fuel chamber 20 by the booster Venturi tube 106.

The booster 106 receives its supply of air through a duct 108 whose inlet end is controlled by a choke plate 110 mounted on a pivot 112. Choke plate 110 has an elongated opening 114 which in the normal position of the choke plate permits free entrance of air into duct 108. As the choke plate 110 is moved from normal running position toward full choke position, the elongated opening 114 progressively restricts the entrance to duct 108 until the full choke position. Only a very small amount of air is permitted to enter duct 108, thereby reducing the effectiveness of booster 106 and facilitating easy starting of the engine.

The air entering booster 106 from duct 108 passes into the restricted throat of the booster wherein a suction is created. Radial ports 116 connect the interior of this throat with an annular space 118 communicating with upwardly inclined bore 120 whose upper end connects with a horizontal bore 122 leading to a downward passage 124 opening into the upper end of fuel chamber 20.

Booster 106 discharges into space 126 which is connected by means of a restricted orifice 128 with a chamber 130 connected with the lower end of each mixing chamber by ducts 132.

5 A metering pin 134 reciprocates in a guide 136 and has an enlarged head 138 operatively connected to an arm 140 rigid with air valve shaft 74.

In Figure 3 the parts are shown in the position 10 which they assume when the air valves are closed, and in this position the small diameter portion 15 of pin 134 is located in orifice 128, thereby providing free discharge for booster 106. As the air valves open under the influence of the suction 20 created in the mixing chambers, the pin 134 is raised to move the tapered portion 142 into the orifice 128 and thereby progressively decreasing the opening through this orifice and correspondingly restricting the discharge of the booster 106 25 so that the booster always maintains the same degree of suction in the fuel chamber 20 during normal operation of the carburetor.

The air horn 70 is provided with an external shoulder 144 to facilitate the attachment of a 25 silencer and air cleaner to the carburetor, if desired.

The invention disclosed herein is an improvement over Serial No. 7,770, filed February 23, 1935.

While I have illustrated and described only one 30 embodiment of my invention, it is to be understood that my invention may assume various forms and that the scope of my invention is to be limited solely by the following claims.

I claim:

35 1. In a down draft carburetor of the class described, the combination of a nozzle, a mixing chamber receiving the discharge from said nozzle, an air inlet for said mixing chamber, a valve controlling said inlet, a pivotal mounting for said 40 valve, said mounting having an axis a baffle located immediately below said valve and parallel with said axis, said baffle extending an appreciable distance in the direction of flow through the mixing chamber to prevent eddying of air 45 passing said valve, and means for supplying fuel to said nozzle.

2. In a down draft carburetor of the class de-

scribed, the combination of a nozzle, a mixing chamber into which said nozzle discharges, an air inlet for said mixing chamber, a disk valve controlling said inlet, a pivotal mounting for said valve, said mounting having an axis, a combined stabilizer and baffle located adjacent to and parallel with the axis of said pivotal mounting upon the suction side thereof, said stabilizer and baffle extending an appreciable distance in the direction of flow through the mixing chamber, and means 10 for supplying fuel to said nozzle.

3. In a carburetor of the class described, the combination of a pair of nozzles, a separate mixing chamber for each nozzle, an inlet for each mixing chamber, a valve for each inlet, a member 15 extending across both inlets on the suction side thereof, said member extending in a plane parallel to the axes of said inlets and constituting a baffle for each, and means for supplying fuel to said nozzles.

4. In a down draft carburetor of the class described, the combination of a mixing chamber, an air inlet for said mixing chamber, a throttle bore constituting an outlet for said mixing chamber, a valve in said inlet, said valve having an eccentric pivotal mounting, a plate having its upper end immediately below said mounting and extending downwardly therefrom to a point as low as the lowest point reached by any portion of said 25 inlet valve, a nozzle discharging into said mixing chamber at a point below said plate and substantially midway between said plate and the wall of said chamber farthest from said plate, and means for supplying fuel to said nozzle.

5. In a carburetor of the class described, the combination of fuel feeding means, a pair of valves for admitting secondary air for admixture with the mixture supplied by said fuel feeding means, a fuel chamber from which said fuel feeding means draws fuel, a booster for creating a 40 suction in said fuel chamber, means for controlling the degree of suction produced by said booster, and a connection between said last-named means and both of said valves whereby the 45 operation of said booster is coordinated with the operation of both of said valves.

ROBERT F. BRACKE.
